W. LISSY

MITER SQUARE

Filed Dec. 21, 1925

William Lissy Inventor

By Herbert E. Smith

Attorney

UNITED STATES PATENT OFFICE.

WILLIAM LISSY, OF SPOKANE, WASHINGTON.

MITER SQUARE.

Application filed December 21, 1925. Serial No. 73,583.

My present invention relates to improvements in miter squares of the straight edge type comprising a stock and a pivoted, slideable, and detachable blade whereby the blade and stock may be arranged at various angles, as a single straight edge ruler or the parts alined as a marker. The instrument is capable of adjustment on its pivot at various angles for use in co-operation with radial markings as a miter square; it may with facility be arranged for use in co-operation with a pencil for a marker within a wide degree of dimensions; and in addition to its use as a single straight edge or ruler the instrument may readily be converted into a try-square.

The invention consists in certain novel combinations and arrangements of parts whereby the instrument may readily be adapted for the above and other uses, as will hereinafter be more fully pointed out and claimed.

In the accompanying drawings I have illustrated several uses of the instrument in which the physical embodiment of the invention shows the combinations and arrangements of parts according to the best mode I have thus far devised for the practical application of the principles of my invention.

Figure 1 is a perspective view of the instrument used as a miter square. Figure 2 is a perspective view of the instrument used as a marker. Figure 3 is a plan view of the instrument converted into a straight edge, and in dotted lines shown as a try-square. Figure 4 is an enlarged detail sectional view taken transversely through the center of Fig. 2 at the pivot bolt.

In carrying out my invention I utilize a stock 1 in the form of a wooden bar, rectangular in cross section and preferably provided with metal edges and corners 2. In the upper face of the stock is fashioned a longitudinally extending slot 3 beneath which is an undercut groove 4.

In connection with the stock I utilize a detachable blade 5 capable of being arranged in various relations to the stock and preferably of wood with metal edges and corners 6.

An interchangeable bolt 7 is used near one end of the blade, which bolt projects below its under surface and the projecting end of the bolt is fashioned with a non-rotatable head 8 which is retained and adapted to slide in the undercut groove 4 while the bolt travels through the slot 3.

A clamp nut 9 is used on the bolt and pro-

vided with a head 10 fashioned for convenience of the thumb and finger in turning it. The nut is seated in a round hole which extends through the blade and the head 10 of the nut is seated in a countersunk, round groove or recess 12 in the upper face of the blade.

For convenience in marking and in other uses of the instrument the blade is fashioned with a longitudinally extending central slot 13 which terminates near one end of the blade and also near the pivotal connection between the stock and blade.

A spirit level 14 is set in the stock between one of its edges and the central longitudinal slot 3 for use in the usual manner.

In Figures 1 and 2 the instrument is illustrated for use as a miter square and as a marker respectively. In the first instance the blade may with facility be adjusted on its pivot to the desired angle conforming to one of the radial lines on the face of the stock and clamped in such position by means of the nut 9. There are two oppositely arranged radial scales, one at each side of the longitudinal center of the stock, and the blade may be shifted to either of these scales and adjusted to a desired angle.

In Figure 2 the instrument is used as a marker in connection with a pencil P for marking on a board or plank as B. For this purpose the blade is turned on its pivot parallel with the stock and the blade is then adjusted longitudinally of the slot to project beyond the end of the stock the desired distance as indicated on the scales along the sides of edges of the blade. The end of the stock and the underface of the projecting end of the blade thus form an accurate and stable guide, after the nut 9 has been clamped tight, for the pencil P.

In addition to these uses the instrument is adapted for use as a single straight edge as in full lines Figure 3, or as a try square as indicated by the dotted lines for the blade in said figure. For this purpose the blade is provided with a longitudinally extending bolt 15 at its end opposite to the pivotal end of the blade, and the bolt is seated in a longitudinally extending opening in one end of the blade. The bolt is fashioned with an integral T-head 16 which is normally retracted in a socket 17 in the end of the blade as seen in Fig. 1.

This T-head of the bolt is adapted to selectively engage either a cross groove 18 fash-

ioned at the end of the stock when the instrument is used as a ruler or straight edge, or the head may engage a longitudinally extending socket 19 near the opposite end of the stock 5 and located in one of its side edges.

A usual clamp nut 20 is provided for the bolt 15 for locking the bolt in position.

The T-head makes a tight frictional engagement and close fit with the walls of the 10 cross groove 18 or the walls of the socket 19 of the stock. Thus when used as a single straight edge or ruler as in full lines Figure 3 the blade and stock are first disconnected at their pivotal points, and then the T-head 15 is loosened by unscrewing the nut 20. The T-head is then slid from one side into the groove 18 and the blade is thus brought into alignment with the stock and the parts are clamped together by turning nut 20.

20 When used as a try-square as indicated by dotted lines in Figure 3, the detached blade is turned at right angles to the stock and the

projected T-head of the bolt is first slid into the open end of slot 19 and then forced 25 into frictional contact with the walls of this longitudinally extending groove 19 of the stock by turning the nut 20.

It will be apparent that various other adjustments and uses may be devised for the instrument by those familiar with carpentry 30 and like trades.

Having thus fully described my invention what I claim as new and desire to secure by Letters Patent is:

The combination with a stock having an undercut, transverse, end groove, of a blade and a bolt mounted therein and movable longitudinally thereof, a T-head on one end of the bolt for co-action with said end groove, 40 said stock also being formed with an undercut side socket adapted to receive said T-head, and a clamp nut on the bolt.

In testimony whereof I affix my signature.

WILLIAM LISSY.
